CRIMPING TOOL

Gustaf Rudolph Lawson, Willingboro, N.J., assignor to
AMP Incorporated, Harrisburg, Pa.

Filed June 8, 1972, Ser. No. 261,139

Term of patent 14 years

Int. Cl. D8—05

U.S. Cl. D8—51

FIG. 1 is a perspective of a preferred crimping tool according to the present invention;

FIG. 2 is an elevation of the obverse side of the crimping tool as illustrated in FIG. 1;

FIG. 3 is an elevation of an end of the crimping tool as illustrated in FIG. 2;

FIG. 4 is an elevation of the reverse side of the crimping tool as illustrated in FIG. 2; and

FIG. 5 is a plan view of the crimping tool as shown in FIGS. 1 and 2.

I claim:

The ornamental design for a crimping tool, as shown and described.
